UNITED STATES PATENT OFFICE

113,391

DESIGN FOR A SHOE

Roy Maling, West Roxbury, Mass.

Application November 1, 1938, Serial No. 80,822

Term of patent 3½ years

To all whom it may concern:

Be it known that I, Roy Maling, a citizen of the United States, residing at West Roxbury, in the county of Suffolk and State of Massachusetts, have invented a new, original, and ornamental Design for a Shoe, of which the following is a specification, reference being had to the accompanying drawing, forming part thereof.

In the drawing:

The figure is a side elevation of a shoe showing my new design. The design is substantially the same on both sides of the shoe.

The essential features of the invention reside in the combination of a plurality of relatively

thick sole platforms, and a plurality of correspondingly thick heel laminations terminating in a composite wedge at the shank of the shoe, with piping of contrasting aspect intervening between the said platforms and between the said laminations. As the design is applicable to shoes of various shapes and styles, the representation of shoe upper is conventional, for showing an application of the design.

I claim:

The ornamental design for a shoe, as shown and described.

ROY MALING.
